(57) CLAIM

The ornamental design for a display screen or portion thereof with icon, as shown and described.

DESCRIPTION

FIG. 1 is a front view of a first embodiment of a display screen or portion thereof with icon showing our new design; and,

FIG. 2 is a front view of a second embodiment of a display screen or portion thereof with icon showing our new design. The broken lines in the drawings show the display screen or portion thereof that form no part of the claimed design.

1 Claim, 2 Drawing Sheets

FIG. 2
